Attorney.

UNITED STATES PATENT OFFICE

2,181,194

BURIAL VAULT

Arthur Martin, Arthur, Ill.

Application November 14, 1938, Serial No. 240,210

2 Claims. (Cl. 72—7)

This invention relates to burial vaults and has for its principal object the provision of an improved vault.

A further object of the invention is to provide a vault comprising a chamber of cementitious material and a metallic liner and highly effective means for securing the elements together.

The invention will readily be understood from the following description of a preferred embodiment thereof, together with the accompanying drawing, in which

Fig. 1 is a perspective view of a burial vault embodying my invention;

Fig. 2 is a sectional elevation through said vault, the section being taken on the line 2—2 of Fig. 1;

Fig. 3 is a sectional detail view showing the manner in which the elements are associated; and

Fig. 4 is an elevational view showing the lining and reinforcement in assembled relation, part of the reinforcement being broken away for clarity.

Referring to the drawing, the reference numeral 10 designates a metal liner which is in the form of an integral chamber which is adapted to be superimposed upon a casket during interment. This chamber comprises side walls 11, end walls 12, and a top wall 13. The top wall 13 is connected directly to the end walls 12 and is connected to the side walls 11 by filets 14. The side walls 11 and end walls 12 are provided at their lower edges with an integral outwardly projecting flange 15 which extends below the walls 16 of the main body 17 of the vault.

The liner 10 is preferably made of metal such as steel, stainless steel, Monel metal or the like and its inside surface and the lower surface of the flange 15 are preferably brought to a high finish.

In order to secure the liner 10 to the body 17 of the vault, without marring the attractive finish of the interior of the liner, I weld relatively short pins or pieces of metal rod 18 to the exterior of the walls 11 and 12 and to the upper surface of the flange 15. As shown in the drawing these pins are welded to a wall or to the flange so that they are located substantially at right angles thereto, one end of each pin being welded to a wall or the flange 15.

As shown in the drawing, I prefer to weld three pins 18 to the flange 15 along each side wall 11. To each side wall 11 I prefer to weld a similar number of pins adjacent and immediately above the pins on the adjacent flange 15. I also prefer to weld a similar number of pins 18 near the upper end of the wall 11 in alignment with the pins on the flange 15 and near the lower edge of the wall.

On each end wall 12 I prefer to weld two pairs of pins 18. One pair is located near the upper edge of the wall and the other pair is located near the lower edge of the wall. Two pins 18 are welded to the flange 15 adjacent the lower edge of each end wall 12 near the lowermost pins on said end wall.

In fabricating the vault the pins 18 are welded in position as indicated, the exterior of the liner, and the pins, is preferably coated with a layer of asphalt paint 19, a suitable reinforcement 20 20 is placed over the liner 10 and the cementitious body 17 is formed around the liner with the aid of suitable forms or molds.

Having thus described my invention, I declare that what I claim is:

1. A burial vault comprising a cementitious body, an integral metal lining therefor having a high interior finish, said lining comprising a flange completely underlying the sides of said body, and pins welded in abutting relation to the upper side of said flange and to the exterior of said lining, said pins extending into said cementitious body and securing the lining within the body.

2. A burial vault comprising a cementitious body including a reinforcement, an integral metal lining therefor having a high interior finish, said lining comprising a flange completely underlying the sides of said body, pins welded in abutting relation to the upper side of said flange and to the exterior of said lining, said pins extending into said cementitious body and securing the lining within the body, and an asphalt coating between said lining and pins and said cementitious body.

ARTHUR MARTIN.
